UNITED STATES PATENT OFFICE.

HASTING P. HOWARD, OF MEMPHIS, TENNESSEE, ASSIGNOR OF ONE-HALF TO ALBERT S. COOK, JR., OF MEMPHIS, TENNESSEE.

STORE.

Application filed November 30, 1921. Serial No. 518,904.

To all whom it may concern:

Be it known that I, HASTING P. HOWARD, a citizen of the United States, residing at Memphis, in the county of Shelby and State 5 of Tennessee, have invented certain new and useful Improvements in Stores, of which the following is a specification.

This invention relates to store equipment and has for its object the provision of means 10 whereby customers may be served without being under the necessity of entering the building and also to provide means whereby customers who may prefer may enter the building and select articles without requiring 15 the services of a large number of attendants, the articles selected being paid for at a settlement station located within the store room. The invention also provides novel means whereby customers desiring a particular article may be served at the outside of the building.

The invention is illustrated in the accompanying drawings, in which—

Figure 1 is a perspective view of a store 25 room equipped in accordance with my invention;

Fig. 2 is an enlarged sectional elevation 30 of the means for supplying customers at a window;

Fig. 3 is an enlarged perspective view of 35 the cash carrier and the means for operating the same whereby a customer who is to be served at the outside of the building may transmit money in payment of his desired purchase to the cashier;

Fig. 4 is an elevation of the means provided to accommodate customers of low stature;

Fig. 5 is a detail view of the cash carrier.

In the drawings, the reference numeral 1 40 indicates the front wall of a store room which front wall may be of any desired architectural structure provided that it be equipped with a series of sales windows 2 extending across the front of the building 45 at a proper height from the ground. As shown more particularly in Fig. 1, the building is provided with an entrance 3 and within the store room spaced from the front wall thereof, is a transverse partition 4.

At the center of the partition 4 is a desk or counter 5 which constitutes a settlement station where customers may pay a cashier for their selections, the desk or counter being entered through a gate 6 which may be of any

preferred form. At each side of the desk is a turnstile 7 which will permit egress of customers, and adjacent one side wall of the store room an entrance 8 is provided, preferably in the form of a vestibule door 60 disposed between the adjacent exit turnstile 7 and the side wall of the room. At the opposite end of the partition 4, a turnstile 9 is provided to constitute an additional exit and disposed parallel with the adjacent side wall of the room is a longitudinal partition or rail 10 which, with the side wall of the room, defines a hall or passageway leading to the said turnstile 9. One or more gates 65 11 may be provided in the partition to facilitate exit from the store room in the event of fire or other emergency. Disposed transversely of the store room adjacent but in rear of the cashier's desk 5 is a basket rack 12 which includes a shelf 13 inclined 70 downwardly toward the entrance 8 so that baskets placed upon the said shelf will gravitate toward the entrance aisle where they may be readily reached by entering 75 customers.

Upon reference to Figs. 1 and 2, it will be noted that a shelf or counter 14 is provided at the rear of the windows 2 and supported by the said shelf or counter and by suitable brackets 15 extending from the ceiling of 80 the store room are delivery chutes 16, it being the intention to provide one of these chutes leading from a point convenient to the cashier's desk to each of the windows 2.

Also arranged adjacent each delivery chute 85 16 and extending between the cashier's desk and the window 2 which is served by the respective chute, I provide a track 17 upon which a cash carrier 18 is adapted to travel.

As shown most clearly in Fig. 3, the track 90 17 consists of similar vertically spaced wires or rods bent intermediate their ends to form angularly disposed branches or arms. These rods or stout wires are rigidly connected adjacent their bends by a brace 19 and they are 100 also connected at their extremities in any convenient or preferred manner. In the drawing, the front ends of the rods are connected integrally by a bight 20 while their rear ends are connected by a clos-

ing plate 21 fitted upon the ends of the rods and secured thereon by any convenient or preferred means, such as nuts or rivets. Each track is supported by a plate 22 pivoted as at 22^a to a bracket or hanger 22' depend- 105

ing from the ceiling of the store room so that if either end of the track be moved upwardly, the opposite end thereof will move downwardly, and the inner end of the track is disposed 5 immediately adjacent and over the cashier's desk, while the front end thereof is disposed immediately adjacent the serving window 2, as is shown in Fig. 2. Attached to the front end of the track is a cable or 10 other flexible connection 23 which extends from the track up to and over a pulley 24 supported upon the ceiling or the front wall of the building, and from said pulley the connection 23 passes downwardly to the 15 counter or shelf 14 where it may be grasped through the window 2, as will be readily understood. Fitted to the track between the upper and lower rods or members thereof is a flanged roller 25, the portion of the roller 20 between its flanges riding upon the lower member of the track while the flanges engage the sides of the track members and thereby prevent accidental removal of the roller from the track. Hung upon the axle of the 25 roller 25 is a bracket or carrying arm 26, to the free end of which is attached a box or other container 27 in which the customer may deposit money to pay for his purchase. It will be understood that certain articles or 30 groups of articles may be wrapped into bundles ready for delivery and deposited in the delivery chutes, each chute bearing a placard or other announcement whereby prospective customers will be informed of the 35 character of the articles which may be obtained from any particular chute and the price to be paid for the same. A customer finding an announcement of particular articles sought by him will deposit the price of 40 the same in the box or container 27 and by then pulling upon the cable 23 will raise the front end of the track 17 so that the track will tilt about the pivot 22 and cause its inner rear end to move downwardly where it may 45 be reached by the attendant at the cashier's counter. This shifting of the track 17 will cause the cash carrier to roll down the track to the stop or connecting plate 21 where the money may be removed by the cashier and 50 change made if necessary. The cashier will then release the bundle or article in the delivery chute which will thereupon slide out onto the counter or shelf 14 and may be removed by the customer through the 55 window 2.

To control the delivery of articles in the respective chutes 16, each chute is equipped at its front or delivery end with cutoffs or valves which will prevent the passage of the 60 bundles or articles until they are released at the cashier's desk. In Fig. 2, bundles placed in the chute are shown at 28 and they are preferably separated by division blocks or spacers 29 so that the cutoffs or 65 valves will be prevented from striking the bundles and thereby injuring the same. Upon the upper side of the chute is a post 30 and upon this post is fulcrumed a lever 31. A cutoff plate 32 is disposed vertically within the chute near the front extremity 70 of the same and plays through an opening 33 in the top of the chute, a link 34 connecting the upper end of this cutoff with the front end of the lever 31, as clearly shown. A similar plate 35 is connected by 75 a link 36 with the lever 31 adjacent the rear end thereof and this plate 35 is adapted to extend across the chute in the same manner that the front cutoff plate 32 extends across the same. The lever 31 extends rearwardly somewhat beyond the link 36 and the plate 35, and to the rear extremity of the lever, I pivotally attach the upper end of a rod 37 which depends into a tubular casing 38 erected upon the floor of the store 80 room immediately adjacent the chute 16, as will be readily understood. Within the casing 38, the rod 37 is attached to a piston 39 and between the said piston and the bottom of the casing 38 is a coiled spring 40 85 which acts upon the piston to normally hold the same in a raised position. A cable 41 is attached to the said piston 39 and extends therefrom through the floor of the store room and then under the floor to a 90 point below the cashier's desk whence it passes upwardly to said desk where it may be manipulated. It will be understood, of course, that the cable 41 passes over suitable guide pulleys and that a cable is provided for each delivery chute so that the discharge from each chute will be controlled 95 at the cashier's desk. The upper portion of the delivery chute has a hinged bottom 42 which may be swung downwardly, as indicated by dotted lines in Fig. 2, to permit the articles to be readily placed in the chute. A cable 43 is attached to the upper end of this hinged bottom 42 and extends over a 100 guide pulley 44 upon the ceiling of the store room and thence downwardly to the cashier's desk. It will be readily understood that, when the articles are ready to be placed in the delivery chute, the cable 43 is released so that the swinging bottom or 105 door 42 may assume the position shown in dotted lines in Fig. 2. The articles are then placed upon said door with spacers 29 between each two bundles or articles after 110 which the door is returned to its initial 115 position and the bundles and spacers will slide downwardly through the chute until the foremost article reaches the cutoff plate or valve 32. When a sale has been made by the transmission of the proper money 120 to the cashier's desk, the cashier will pull upon the proper cable 41 and thereby rock the lever 31 so that the cutoff plate or valve 32 will be raised and the valve 35 simultaneously lowered. The lifting of the valve 125 130

32 will obviously permit the bundles and spacers to again gravitate through the chute so that the foremost bundle will pass onto the shelf 14 where it may be withdrawn by 5 the customer. The downward movement of the second bundle, however, is temporarily arrested by the lowering of the upper plate or valve 35 into its path, as will be readily understood upon reference to the

10 dotted lines in Fig. 2. When the first bundle has been withdrawn, the cashier releases the cable 41 whereupon the spring 40 will at once return the parts to the normal position, permitting the second bundle to pass 15 to the forward cutoff in an obvious manner.

The merchandise displayed for sale is arranged upon shelves 45 carried by cases 46 which are mounted upon rollers 47 so that they may be easily shifted as may be desired, 20 suitable cards, tags or labels being provided upon each shelf to announce the prices of the displayed articles. The rollers 47 are low but have wide tread surfaces so that they will support the several show cases or shelves 25 in a stable manner. To add to the stability of the display, each show case or set of shelves is equipped near its bottom with swinging hooks 48 adapted to engage eyes 49 on the floor of the store room and thereby 30 prevent accidental shifting of the furniture.

The basket rack 12 is also mounted upon casters or rollers so that it may be readily set at any desired distance from the cashier's desk and the space between the basket rack 35 and the said desk will form a cross aisle through which customers may pass in order that a large number of customers may be accommodated at one time around the desk and congestion in the aisles thereby relieved.

40 To further relieve congestion, I provide a supplemental cashier's desk 50 at the rear end of the hall defined between the partition 10 and the adjacent side of the sales room, some of the cases 46 extending from the end 45 of the partition 10 parallel with the adjacent side wall of the store room to a point near the said desk 50. A cage 51 may be provided around the desk 50 to prevent interference with the work of the attendant and 50 a gate 52 is provided between the desk and the adjacent show case 46 to cut off or retard the passage of customers past said desk. A guard 53 is also provided parallel with the desk and extending rearwardly from the 55 gate 52 so that customers will be obliged to pass close to the desk 50 when seeking to utilize the exit 52.

Reserve stock may be kept in a stock room in rear of the store room, or a plurality of 60 trucks 61 may be provided in the space between the show cases 46 and the rear wall of the store room to carry reserve stock or display goods which are ordinarily displayed in baskets or similar containers. These 65 trucks may be readily moved about from

point to point so that as stock upon the shelves is depleted, fresh stock may be added thereto. It will be readily noted that the show cases 46 are arranged in parallel rows extending longitudinally of the store room 70 so that aisles will be provided through which customers may circulate and obtain a view of all the merchandise offered for their selection.

Near the tops of the show cases, I provide eyes or similar devices 54 which are to be engaged by the hook terminals 55 of a track rod or rail 56 extending longitudinally of the show cases or a row of show cases in spaced relation thereto. This track 56 is 75 engaged by a roller 57 at the upper end of a standard or frame 58 rising from a stepped platform 59 equipped with casters or rollers 60 whereby it may be easily moved over the floor of the store room. Obviously, children or persons of low stature may, by the aid of this stepped platform or car, easily reach the articles upon the upper shelves.

From the foregoing description, taken in connection with the accompanying drawings, 80 it will be seen that I have provided a store in which the overhead expense will be very materially reduced by making unnecessary the employment of a large number of clerks and salesmen inasmuch as the customers 85 may serve themselves. In the practice of my invention, congestion within the store is reduced to a minimum inasmuch as I provide two exits at the main settlement station and also provide an auxiliary settlement 90 station at the rear of the store room from which a separate passage leads to the main entrance and exit. Further, as a series of sales windows extend across the front of the building from which customers may be 95 served without being required to enter the building, a large number of customers may be served rapidly and easily and without interfering with or blocking the way of customers who may contemplate a more 100 extended list of purchases. It is to be noted especially that the show cases or shelves are all portable or mounted on rollers so that the merchandise to be displayed may be arranged in units and any one unit may be 105 changed without requiring a shifting of other units and as the stock in one unit is depleted by selections therefrom, a complete filled unit may be substituted therefor by merely removing the depleted unit and rolling into its place a previously prepared full unit.

Moreover, in the event of fire or other panic-creating emergency the plurality of exits provided in the partition 4 will permit the customers and attendants to very 110 quickly leave the store room and also will permit the shelves or show cases to be readily rolled out of the building.

Having thus described the invention, what is claimed as new is:

1. In a store, a store room having a series of sales windows extending along its front wall, merchandise display members arranged within the store room, a settlement station disposed between the sales windows and the merchandise holders, means controlled at the settlement station for delivering merchandise at the sales windows, and means operable at the sales windows to transmit payment for purchases to the settlement desk.

2. In a store, a store room having a series of sales windows extending across its front end, a controlling station within the store room, chutes extending from said station to the sales windows through which articles of merchandise may pass from the said station to the sales windows, valves mounted in said chutes to control the discharge of articles from the chutes, and means whereby said valves may be operated from the said station.

3. In a store, a store room having a series of sales windows extending across its front end, a controlling station within the store room, delivery chutes extending from said station to the sales windows, the upper portions of said chutes having downwardly swinging bottoms, means controlled at the said station for operating said hinged bottom and holding it normally in raised position, and means operable from said station to control the passage of articles through the chutes.

4. In a store, a store room having a series of sales windows extending across its front end, a controlling station within the store

room, delivery chutes extending from said station to the sales windows, a lever mounted for rocking movement upon each chute, cut-off plates depending from the said lever at opposite sides of its fulcrum into the chute, and operating means extending from said lever to the controlling station.

5. In a store, a store room having a series of sales windows extending across its front end, a controlling station within the store room, means operable at said station to deliver goods at the sales windows, movable tracks supported within the store room and extending between said station and the sales windows, cash carriers mounted on said tracks, and means for tilting said tracks whereby the cash carriers may be caused to travel between the sales windows and the controlling station.

6. In a store, a store room having a series of sales windows extending across its front end, a controlling station within the store room, tracks each consisting of upper and lower members suspended within the store room for tilting movement and extending between the respective sales windows and the controlling station, a flanged roller disposed between the upper and lower track members and arranged to travel along the same and be guided thereby, a container hung upon said roller, and means for tilting the track whereby the roller and the container hung thereon will be caused to gravitate between the controlling station and the sales window.

In testimony whereof I affix my signature.
HASTING P. HOWARD. [L. s.]
